Wesley F. Junker, Copiague, and Alan A. Hicks,
New York, N. Y.

Application March 26, 1957, Serial No. 45,447

Term of patent 14 years

(Cl. D58—4)

The characteristic features of our design for the clothes hamper disclosed reside in the cover portions having the configuration shown. The sides and rear, not shown, are of the same appearance as the front.

We claim:

The ornamental design for a clothes hamper, as shown and described.
